(57) **CLAIM**

The ornamental design for an outsole bottom as shown and described.

DESCRIPTION

FIG. 1 is a perspective view of the outsole bottom in accordance with my new design;

FIG. 2 is a front side view thereof;

FIG. 3 is a rear side view thereof;

FIG. 4 is a left view thereof;

FIG. 5 is a right view thereof;

FIG. 6 is a top view thereof; and,

FIG. 7 is a bottom view thereof.

The dash-dash broken lines shown in the drawings represent environmental structure showing parts of the upper and shoe midsole periphery as well as portions of the outsole bottom that form no part of the claimed design. The dot-dashed broken lines define the bounds of the claimed design and form no part thereof.
